UNITED STATES PATENT OFFICE.

JONATHAN J. HOYT, OF CHELMSFORD, MASSACHUSETTS, ASSIGNOR TO
EDWARD F. RICHARDSON, OF SAME PLACE.

CASE FOR PRESERVING FOOD.

SPECIFICATION forming part of Letters Patent No. 313,076, dated March 3, 1885.

Application filed July 15, 1882. (No model.)

To all whom it may concern:

Be it known that I, JONATHAN J. HOYT, of Chelmsford, in the county of Middlesex and Commonwealth of Massachusetts, have invented certain new and useful Improvements in Cases for Preserving Food, of which the following is a specification.

My invention relates to such cases as are provided with external screw-threads to engage sheet-metal sleeve-nuts which hold the covers of such cases in place; and it consists in means for strengthening such nuts at the sides and tops thereof.

In the accompanying drawings, Figure 1 is a side elevation of such a case and sleeve-nut with my improvement applied thereto; Fig. 2, a plan of the same; Fig. 3, a central vertical section of the case, cover, and sleeve-nut.

A is a cylindrical case provided near its top with an external screw, B. This case may be like the fruit-jars commonly used. The opening in the top of the case is closed by a circular cover, C, between which and the case may be interposed a gasket or packing, C'. All of these parts may be of known construction and are not of my invention. The sleeve-nut D, stamped out of sheet metal, and having a screw-thread (to engage with the thread B on the case A,) and having an internal flange, D', which rests upon the top of the cover C, is of the usual construction, except that it is strengthened and stiffened by three or more vertical stays, D², which are soldered to the sides and top of said nut. These stays are preferably made of round wire, which is bent at about a right angle, so as to stand vertically on the side and radially on the top of said sleeve-nut. The inner side of the vertical part of the stay may be notched to fit the external threads of the nut, as shown at d, Figs.

1 and 3. The object of these stays is to prevent the threads of the nut from being obliterated by repeated use and the consequent smoothing down of the corrugations which form the threads to prevent the nut being torn apart between the threads, and to obtain at a less expense a lighter nut (struck up from sheet metal,) which shall be equally as strong as a cast-metal nut. By having the stays reach over the top of the flange of the nut, the flange is so stiffened that a greater pressure can be brought on the cover. It is common to form the sleeve-nut in one piece with the cover.

I am aware that a single vertical wire has been soldered to the side of a sleeve-nut or cover to engage with a wrench, by which such nut or cover is screwed on, but as the strength of the vertical part of the nut or cover is only as great as the strength of its weakest part, such a single vertical rib has practically no effect to strengthen the cover.

I am also aware that cast-metal screw-covers have been made with vertical ribs to enable such covers to be more firmly grasped by the hand.

I claim as my invention—

1. The combination of the sheet-metal sleeve-nut D, and three or more vertical stays, D², secured to the outside of said nut, as and for the purpose specified.

2. The combination of the sheet-metal sleeve-nut D, provided with an internal flange, D', and three or more vertical stays, D², secured to the outside of said nut and to the top of said flange, as and for the purpose specified.

JONATHAN J. HOYT.
